UNITED STATES PATENT OFFICE.

OSCAR M. CARTER, OF HOUSTON, TEXAS.

ROLLER CUTTER.

Application filed December 23, 1924. Serial No. 757,703.

This invention relates to an improvement in roller cutters especially designed for use on rotary drills.

The object of the invention is the provision of a device of this character which is especially designed for use when rock, packed sand or other hard substances are encountered, the drill and cutter constituting the present invention being designed 10 and adapted to sink the hole more rapidly through such formations than other cutters heretofore proposed.

Other objects and advantages reside in certain novel features of the construction, 15 arrangement and combination of parts which will be hereinafter more fully described and particularly pointed out in the appended claims, reference being had to the accompanying drawings forming a part of 20 this specification, and in which:—

Figure 1 is a view partly in elevation and partly in section showing one embodiment of the invention,

Figure 2 is a fragmentary view with portions of the cutter holder in section to illustrate the mounting of the cutters,

Figure 3 is a detail view in elevation of one of the cutters employed at the forward end of the tool, and

Figure 4 is a diagrammatic view illustrating the paths of rotation of the lower cutters.

Referring to the drawings, the numeral 1 designates a drill stem on which cutters 25 designated generally at 2 and embodying the present invention are mounted. The mounting of the cutters on the drill stem and the control of these cutters form no part of the present invention.

The cutters 2 comprise holders or frames 3, which in the operative position, are disposed in angular relation with respect to each other, the holders or frames 3 diverging from each other forwardly. With this ar-

45 arrangement a substantially V-shaped recess 4 is provided between the holders or frames 3. Series of roller cutters designated generally at 5 are provided along each edge of the V-shaped recess 4. The roller cutters 5 operate in part in openings 6 formed in the frames or holders 3, but project from said openings 6 into the recess 4 as shown in the drawings. The cutters of the series 5 are rotatably mounted on shafts 7 carried in 50 bearings 8 provided on the holders or frames 3. The shafts 7 are suitably secured in po-

sition as by means of pins 9. The roller cutters 5 take the form of disks having teeth 5^a on their periphery. With the arrangement shown, a plurality of roller cutters 5 are provided along each edge of the recess 4 so that in operation the roller cutters 5 approximately define a V-shaped recess. The holders or frames 3 are formed with depending or forwardly extending extensions 10 in which short shafts 11 are fixed as by means of pins 12. On the inner ends of the shafts 11 conical roller cutters 13 are rotatably mounted and on the outer ends of these shafts 11 disk-shaped roller cutters 14 are rotatably mounted. The conical shaped roller cutters 13 are constrained to rotate on the shafts 11 by the portions 3^a of the holders or frames 3, and the disk shaped cutters 14 are similarly constrained by means of heads 15 provided on the shafts 11. The holders or frames 3 are so designed that the cutters 13 and 14 on one frame are spaced at a different distance from the axis of rotation than the cutters 13 and 14 on the other side. By virtue of this different spacing of the cutters 13 and 14 the cutters on one side remove or cut away the ridge left between the cutters on the other side.

The cutters 14 are shown in detail in Figure 3, and have a number of long and heavy teeth 16 arranged at spaced intervals around their peripheries. Short teeth 17 are provided between the long teeth 16. With cutters 14 of this character the drilling is periodically permitted to fall with crushing force on the rock or formation, thereby shattering or breaking it up into fine particles which are easily carried to the surface by the mud pump.

On the projecting lateral edges 19 of the frames 3 reaming roller cutters 20 are provided, the cutters 20 being rotatably fitted on shafts 21 pinned as at 22 to the frames 3.

With a cutter such as described a cone is formed in between the roller cutters 5 and this has a marked tendency and influence to keep the hole straight. This feature in combination with the different spacing of the cutters 13 and 14 whereby a complete action at the forward end of the tool is had provides for a very effective cutting action. The effectiveness of the cutting action is enhanced by the action of the roller cutters 14 which cause the drill to periodically rise and fall, and on the fall to strike the for-

mation forcibly to shatter and crush the same. It is by virtue of these features that the present cutter is able to sink a hole much more rapidly than other cutters heretofore proposed through rock, packed sand or other hard substance.

I claim:-

1. In a drill of the character described, a pair of inclined frames defining a V-shaped recess between them, and roller cutters mounted on the frames and operating along the edges of said V-shaped recesses.
2. In a drill of the character described, a cutter having roller cutters at its forward end provided with long and short teeth, the long teeth being designed to raise the drill and permit the same to fall to cause the cutter to exert a shattering action on the formation.
3. In a rotary drill, a cutter having roller cutters at its forward end, and having means periodically raising the drill and per-

mitting the same to fall so that the cutters exert a shattering action on the formation.

4. In a drill, a cutter including a pair of diverging frames defining a V-shaped recess, a series of roller cutters arranged along the edges of the recess, said frames having extensions, shafts mounted on the extensions, conical cutters arranged on the inner ends of the shafts, and roller cutters arranged on the outer ends of the shafts.

5. In a drill, a cutter including a pair of diverging frames defining a V-shaped recess, a series of roller cutters arranged along the edges of the recess, said frames having extensions, shafts mounted on the extensions, conical cutters arranged on the inner ends of the shafts, roller cutters arranged on the outer ends of the shafts, and reaming cutters rotatably mounted on the sides of said frames.

OSCAR M. CARTER.
